UNITED STATES PATENT OFFICE.

LOUIS INTIERI, OF BROOKLYN, NEW YORK.

DESIGN FOR A BIRDCAGE.

Application filed November 1, 1926. Serial No. 19,557. Term of patent $3\frac{1}{2}$ years.

To all whom it may concern:

Be it known that I, LOUIS INTIERI, a subject of Italy, residing at 397 Linwood Street, in the borough of Brooklyn, city and State of New York, have invented a new, original, and ornamental Design for a Birdcage, of which the following is a specification reference being had to the accompanying drawing, forming a part thereof.

The drawing shows a front perspective view of a bird cage, showing my new design.

I claim:

The ornamental design for a birdcage, as shown.

LOUIS INTIERI.
